(57) **CLAIM**

The ornamental design for an adjustable shelf support clip, as shown and described herein.

DESCRIPTION

FIG. 1 is a perspective view of an adjustable shelf support clip showing the new design;

FIG. 2 is a front view thereof;

FIG. 3 is a side view thereof, the opposite side being the same as this side;

FIG. 4 is a back view thereof;

FIG. 5 is a top view thereof; and,

FIG. 6 is a bottom view thereof.

The broken line portions of the disclosure are for illustrative purposes only and form no part of the claimed design.
